UNITED STATES PATENT OFFICE.

ARTHUR T. MCWANE, OF BIRMINGHAM, ALABAMA.

WINDOW GUARD.

Application filed June 8, 1923. Serial No. 644,261.

My invention relates to an improvement in window guards and has for its object to provide a guard operable independently of the window sash and adapted to be so mounted as to be normally concealed, there being key controlled means to lock it in one or more operating positions.

It is a further distinctive feature of my invention that by arranging a guard of this type in the guides for the upper or outer sash it is adapted when locked in position not only to serve as a guard for the lower sash opening but also to lock the upper sash in raised position so that access can be had only by breaking the glass in the latter sash or in both sashes when the lower sash is raised.

My invention further contemplates adapting the guard to move vertically, in which event it is retracted into the wall space below the window frame, or to move horizontally, in which event it is retracted into the wall space at the desired side of the sash, and it is obvious that in either form my invention is adapted for use with both sliding or casement windows.

The novel features of my invention and its structural advantages can be better understood by reference to the accompanying drawings which illustrate only the preferred embodiments of my invention, and in which:

Fig. 1 shows a vertically sliding guard in partial front elevation.

Fig. 2 is a cross-sectional view taken on the line 2—2 of Fig. 1 with a lock which would not appear in this view in dotted lines to show its relation with the other parts.

Fig. 3 is a view in section through the upper sash guide showing that sash and the guard in elevation in raised positions with the lock in front elevation.

Fig. 4 is a front elevation of a window with a laterally sliding guard shown locked in operating position.

Fig. 5 is an enlarged detail view of a portion of the guard showing the lock in elevation and a portion of the guides for the guard bars.

Similar reference numerals refer to similar parts throughout the drawings.

In the embodiment of my invention illustrated in Figs. 1 to 3, I show a window frame 1 which may be of ordinary construction for vertically slidable lower and upper sashes 2 and 3, respectively. The frame is

provided with the usual guide rails 4 forming guides 5 and 6, respectively, for the sashes 2 and 3. I provide in the bottom sill 7 of the sash frame, in line with the guide 6 for the outer or upper sash, a series of openings 8 which are adapted to receive the vertical bars 9 forming the guard, which bars are connected at their top by a cross bar 10. There is also connected to this cross bar at each side a bar 11 which is fitted to slide in the sash guide 6 in the same manner that the sash 3 does, and suitable openings are provided for these side bars 11 in the bottom sill. In one of the side bars 11 I provide the notches 12 and 13 which open towards the sash guide 6 and are adapted to co-act with a spring latch 14 which projects through the outer sash guide 6 near the upper end thereof. This latch is of the spring-pressed retractable type in common use mounted in a barrel 15. The latch is retracted against the action of its spring bar by any suitable key controlled lock mechanism, such for instance, as the typical Yale lock 16 having a rotatable barrel with a suitable retracting connection (not shown) to the spring latch. This lock mechanism is merely conventionally shown as it may be of any desired character and mounted in any desired manner so long as it will serve to control the unlatching of the guard so that the latter can, when desired, be lowered. I provide the notches 12 in order that the guard may be locked in position sufficiently below its uppermost position to enable the upper sash to be lowered slightly for ventilating purposes, say about six inches. When the guard is not needed, the key controlled latch is retracted, and the guard is lowered onto the bottom sill 7 where it is concealed sufficiently not to affect the appearance of the window. When it is desired again to use the guard, it is raised until one or the other of the notches engages the latch 14, and in this position the guard is locked so as to close the lower half of the window opening so effectively as to protect the same, while preventing the upper sash being lowered. Thus to break and enter the glass in the upper sash must be broken.

Referring to the construction illustrated in Figs. 4 and 5, I show the window frame 1 provided with a series of lateral openings 17 in the sash guide 6 and through these openings pass the bars 9 and the side bar 11 of the sash guard which in this construc-

tion are horizontally disposed. The lower side bar of the guard rests and slides upon the sill 7 which in this construction is left solid. The cross connecting bar 10 of the guard, when in operating position, is received in and fits snugly into the guide 6 on the side of the sash frame opposite that having the openings 17.

In Figs. 4 and 5 I show the customary studding 18 in the wall and as a preferred arrangement I bore openings in the studding aligning with the openings 17 and mount therein suitable guides 19 for the guard members 9 and 11. These guides as illustrated are formed by sections of piping but they may be made up and mounted in any suitable way. The latch notch 20 is provided in such position on the top bar 11 that it will come opposite the latch 14 when the guard is in closed position. In this arrangement the latch is disposed above the guard and is pressed downwardly by its spring into engagement with the top guard member 11. The key controlled mechanism for operating the latch is the same as that already described. It is to be noted that the sash guide 6 on the side of the frame towards which the rail 10 is moved to retract it, is provided with a countersunk recess 21 into which the rail 10 moves and seats with its outer face flush with the undisturbed wall of the guide. Thus the guard itself forms part of the guide 6 for the upper sash as it is lowered and by this means it is effectually concealed and housed so that its presence, when not in use, is not observable.

To utilize a guard of this type it is only necessary to grasp the guard bar 10 by the finger grips 22 therein and slide it across the window opening until the latch 14 snaps into the notch 20, in which position it holds the guard so that it cannot be retracted and in such position the guard holds the upper sash 3 raised and acts as a protective means in the same manner as described in connection with the vertically sliding guard. It is to be understood that the guards may be of any suitable shape and design, that shown

being merely illustrative, and that the means to lock or latch the guards in operating position may be changed as desired.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In combination with a sash frame having guides for its upper and lower slideable sashes, of a guard comprising a rigid frame with a vertical bar at one side and horizontal bars attached thereto at one end and left free at the other end, and tubular guides mounted to open through a sash guide at one side and adapted to receive said bars, there being a countersunk recess in the sash guide to seat said vertical bar flush with said sash guide.

2. The combination with a window frame having a sash way provided with a series of openings and guides rigidly mounted in horizontal alignment with said way openings, of a window guard comprising a rigid frame composed of horizontal rods, a vertical connecting bar for one end of said rods, the free ends of said rods being slideable through said openings and guides, said sash way having a countersunk recess to receive said vertical bar, and key controlled means to lock said frame in its operating position.

3. The combination of elements as described in claim 2, in which the guide for one of the rods is spaced inwardly from said way, and a key controlled latch mechanism adapted to co-act with the bar between the sash way and its guide to lock the guard in operating position.

In testimony whereof I affix my signature.

ARTHUR T. McWANE.
